ANODE SALVAGING

George W. Veale, Grass Lake, Mich., assignor to
 Eaton Manufacturing Company, Cleveland,
 Ohio, a corporation of Ohio

Application December 4, 1937, Serial No. 178,103

1 Claim. (Cl. 204—288)

This invention relates to the art of electroplating and as its principal object aims to provide a novel device and method for salvaging the stubs remaining from anodes which have been used in an electroplating bath.

Another object of my invention is to provide a novel method for salvaging anode stubs comprising mounting the stubs in spaced relation on an electrically conducting support and then suspending the assembly thus formed in an electroplating bath as an anode.

Still another object of my invention is to provide a simple and inexpensive device for carrying out this salvaging method comprising an elongated electrically conducting member adapted to be suspended in an electroplating bath and having means for mounting the anode stubs thereon in spaced relation.

A further object of my invention is to provide a simple and inexpensive device for salvaging the stubs of anodes having threaded openings therein, comprising an elongated electrically conducting member adapted to be suspended in an electroplating bath and having pins projecting therefrom which are threaded and are formed of the same material as the stubs, and upon which the stubs are adapted to be mounted.

Yet another object of my invention is to provide an anode stub salvaging device of the type mentioned in which the electrically conducting member has a protective coating thereon of substantially electrolytically-inactive material.

Other objects and advantages of my invention will be apparent from the following description when taken in conjunction with the accompanying sheet of drawings, in which

Fig. 1 is a perspective view showing electroplating apparatus with which my salvaging device and method may be used.

Fig. 2 is an elevational view showing an anode of the type commonly used in electroplating work.

Fig. 3 is an elevational view showing the stub which remains after the anode has been eaten away in the electroplating bath.

Fig. 4 is an end view of the stub, and

Fig. 5 is an elevational view, with parts broken away, showing a novel device for salvaging the anode stubs, and which may be used in carrying out my novel method.

More detailed reference will now be made to the accompanying drawing in describing my novel device and method for salvaging anode stubs. Although the drawing shows what I now regard to be the preferred form of my salvaging

device, it should be understood that the invention may be embodied in various other devices and in various other steps of procedure than those hereinafter specifically described.

5 In Fig. 1 of the drawing I show electroplating equipment with which my novel salvaging device and method may be used. This equipment may include a suitable tank 10 adapted to contain an electroplating solution or bath 11, and electrically conducting bars 12 and 13 extending across the top of the tank and from which the anodes 14 and articles 15 to be plated may be suspended, respectively. Conductors 16 leading from a suitable source of current supply are connected with the bars 12 and 13 for passing an electric current through the anodes, the bath, and the articles to be plated.

10 The anodes 14 suspended from the bar 12 may be of a type commonly used in electroplating work and, as shown in Fig. 2, may comprise an elongated metal bar of generally oval substantially uniform cross section although bars of any shape may be used. The bars may have a threaded opening 18 in the upper end thereof 15 adapted to receive a hook 20 by which the anode is suspended in the bath. As is well understood in this art, the metal of the anode corresponds with the metal desired to be plated on the articles, for example, the anodes may be bars of nickel.

15 After the anodes 14 have remained suspended in the electroplating bath for a period of time they become eaten away until only a stub 21 remains on the hook 20. When this condition occurs the anode stubs are removed from the bath and are replaced by new anode bars, or by anodes formed by use of, that is, embodying my novel salvaging device to be presently described. After removal of the anodes from the plating bath the stubs 21 are disconnected from the hooks 20. Heretofore these stubs have been disposed of as junk metal, although some attempts have been made to make further use of the stubs in electroplating by suspending them 20 in a basket in the electroplating bath.

25 By my invention the soluble portions or anode stubs 21 can be substantially completely used up in the electroplating bath in a simple, efficient and economical manner. In carrying out this salvaging of anode stubs, I mount a plurality of the stubs in spaced relation on an electrically conducting member or rack and then suspend the assembly thus formed in the electroplating bath as an anode. These anode assemblies can 30 be substituted for some or all of the anode bars

14 shown in Fig. 1, and in this way the stub anodes can be substantially completely used up.

In Fig. 5 of the drawing I show such an anode assembly 22 as embodying my salvaging device and in which the electrically conducting member may comprise an elongated metal bar 23 of square or other suitable cross sectional shape. This member may have a threaded opening 24 in its upper end corresponding with the threaded opening of the anode bars 14 and in which a hook 25 may be mounted for suspending the salvaging device in the electroplating bath. At spaced points along the member 23 I provide devices for mounting the anode stubs 21 thereon, and for these devices I prefer to use pins or studs 26 which are screwed into threaded openings of the member 23 so that the ends of the pins will project from opposite sides of the member. The projecting ends of the pins 26 correspond in size with the threaded openings 19 of the anode stubs, so that these stubs can be readily screwed onto the pins and thereby mounted on the salvaging device.

To avoid contamination of the electroplating solution or bath by the salvaging device I provide the member 23 with a protective coating 27 of substantially electrolytically-inactive material, such as soft vulcanized rubber. To this same end I also form the pins or studs 26 from the same metal as that of which the anodes 14 are formed, that is to say, when the anodes are formed of nickel, these pins will likewise be formed of nickel. In mounting the anode stubs on the salvaging device or rack it may be desirable to prevent the stubs from engaging the protective rubber covering 27, and for this purpose I provide a washer 28 of "Bakelite" or other suitable material around the base of each pin projection.

The member 23 of my salvaging device or rack may be made of a length to accommodate any desired number of the spaced stub-mounting pins 26, but I prefer to make the device of such size or capacity that when stubs of the size usually available are mounted on the pins, the assembly will have a corrosion area or corrosive action substantially equal to that of a standard full size anode. When a desired number of anode stubs 21 have been mounted on the salvaging device in spaced relation, as shown in Fig. 5, the assembly 22 thus formed is suspended as an anode in the

5 electroplating bath and, as the electroplating operation continues, the anode stubs will be substantially completely used up, whereupon the salvaging device may be removed from the solution and another set of anode stubs mounted thereon.

10 From the foregoing description and the accompanying drawing it will now be readily seen that I have provided a novel method as well as a simple and economical device for salvaging anode stubs. By use of my novel device and method the anode stubs can be substantially completely used up in the electroplating bath and a substantial saving thus effected in electroplating work. My device and method for anode stub salvaging also permits 15 corrosion or eating away of the anode material of the stubs at substantially the same rate or speed as for standard new anodes, and this permits a substantially standard or uniform speed 20 of corrosion to be maintained which has not been possible with salvaging methods and devices heretofore available.

25 While I have illustrated and described my novel salvaging device and method in a somewhat detailed manner, it will be understood, of course, that I do not wish to be limited to the precise form of construction and steps of procedure herein disclosed, but regard my invention as including such changes and modifications as do not constitute a departure from the spirit of the invention 30 and the scope of the appended claim.

Having thus described my invention, I claim:

35 An anode structure of the character described comprising an elongated metal member encased in a protective rubber covering and having threaded openings at points spaced therealong, a plurality of threaded pins screwed into said 40 openings and having their threaded outer ends extending beyond the rubber covering, and soluble portions having threaded openings therein and being connected with said elongated member in abutting relation thereto by being screwed onto the pins, said pins being made of the same kind 45 of material as said soluble portions and said soluble portions being of maximum thickness adjacent the end thereof abutting said elongated member whereby the soluble portions will remain connected with the pins until they are substantially used up.

GEORGE W. VEALE.
